(57) **CLAIM**

The ornamental design for a shower head and mount, as shown and described.

DESCRIPTION

FIG. 1 is a front perspective view of a shower head and mount;

FIG. 2 is a rear perspective view thereof;

FIG. 3 is an exploded perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is an exploded left side elevational view thereof;

FIG. 9 is a top plan view thereof; and,

FIG. 10 is a bottom plan view thereof.

The broken lines shown represent portions of a shower head and mount and form no part of the claimed design.
